BATH BENCH

William R. Brewer, 9100 Bartee Ave.,
Arleta, Calif. 91331

Filed Dec. 15, 1967, Ser. No. 9,803

Term of patent 14 year

Int. Cl. D6—01

U.S. Cl. D15—8

FIG. 1 is a left side perspective view taken from the front of a bath bench showing my new design;

FIG. 2 is a top plan view thereof;

FIG. 3 is a rear elevational view; and

FIG. 4 is a left side elevational view of the same.

I claim:

The ornamental design for a bath bench, as shown.
